Inventors

UNITED STATES PATENT OFFICE.

OCTAVE BATTAILLE, OF BASECLES, BELGIUM, AND PIERRE PIPEREAUT, OF PARIS, FRANCE.

APPARATUS FOR SPREADING PYRITES IN ROASTING-FURNACES.

1,089,304.

Specification of Letters Patent. Patented Mar. 3, 1914.

Application filed January 29, 1913. Serial No. 744,915.

To all whom it may concern:

Be it known that we, OCTAVE BATTAILLE, a subject of the King of Belgium, and resident of Basecles, Belgium, and PIERRE 5 PIPEREAUT, a citizen of the French Republic, and resident of Paris, France, have invented certain new and useful Improvements in Apparatus for Spreading Pyrites in Roasting-Furnaces, of which the following is a 10 specification.

This invention relates to mechanical pokers and more particularly to that class of mechanical pokers adapted for use with a furnace adapted for the roasting of pyrites 15 in the manufacture of sulfuric acid.

The object of this invention is to provide a mechanical poker which shall reduce the time necessary for the firing of a furnace of this type to a minimum.

20 A further object of the invention is to produce a device of the character described which shall combine utility, cheapness, and durability.

With these and other objects in view, the 25 invention consists of the peculiar combination and construction of the various parts of a mechanical poker as hereinafter described and more particularly set forth in the appended claims.

30 Referring to the drawings wherein similar reference characters indicate similar parts wherever used, Figure 1 is a side elevation of the device. Fig. 2 is a rear elevation of the device showing a section 35 through the operating mechanism.

The device comprises a framework 1, composed preferably of U-irons bolted together, and mounted upon axles 2, carrying flanged wheels 3, adapted to ride upon rails 4. Two 40 distinct apparatuses are mounted on this framework, one of these apparatuses, A, serving to introduce the charge of pyrites into the furnaces while the other one B comprises the whole working mechanism of the mechanical pokers. The first named apparatus 45 A is composed of a pulley wheel 6 provided with a hollow or solid rim having two projecting flanges 7 upon which a belt 8 is passing this belt being made of any suitable material and being guided by three idlers 15, 16 and 17 one of which ascertains the tensioning by means of a lever 10. The shaft

11 of the pulley 6 is driven by a second ordinary pulley 12 which receives its movement from an electric motor 13 or any other source of motive power. The pulley 6 rotates with such a circumferential speed that the crushed material or pyrite, which is fed by a hopper 14 between the rim and the belt 9 is carried along by the centrifugal force 60 until it reaches the idler 15 where it escapes along a trajectory the amplitude of which varies according to the length of the furnaces.

The apparatus described above is carried by a vertical shaft 18 which when rotated around an axis 20 allows of the jet being directed into the furnaces in order to obtain a perfect spreading of the material. The shaft 18 is screw threaded so that when rotated through the medium of a hand wheel 19 provided with a handle the upper stories of the furnace can be served.

In the actually employed furnaces it takes the stoker at least 5 minutes to introduce 75 into the furnace with the shovel about 140 kilograms. With the aid of the mechanism just described the work will be done in one minute.

The mechanism B of the poker is composed of a vertical framework 21 adapted to pivot at 22 and upon which a truss frame 23 is adapted to rise and descend, this truss frame 23 supporting the two pokers 24 and the electric motor 25 or other source of motive power, as well as all the apparatuses used for reciprocating the pokers.

The apparatus comprises two symmetrically arranged pokers 24 which, however, never work together. It is a well known 90 fact that the temperature of these furnaces is a high one and that when a poker has worked during a certain time, it becomes hot and has a tendency to bend; consequently, 95 when the operator of the apparatus notices a certain flexion during the work, he withdraws it at once and sets the other one going thus allowing the first one to cool down.

The operator, in order to cause a poker to enter the furnace, raises it at its front part 100 by means of the lever 26; if the pyrites have to be pushed back, he causes the head of the poker to trail on the bottom of the furnace; if on the contrary it is desired to pull the

pyrites toward him, he keeps the poker in a raised position out of touch with the pyrites and lets it drop at the end of the furnace.

5 The stroke of the poker is equal to the length of the furnace; the operator by simply maneuvering a hand lever causes it to advance or to move backward at will at a speed which may reach 2 meters per second; 10 he may cause the poker to move the whole forward or backward stroke without any stop or through any part of said stroke. The poker obeys during this movement in the same manner as the poker which is 15 manipulated by the worker's hands in the ordinary furnaces. At the rear part of the truss part is a slot 27 which allows the worker to raise or to lower the poker in certain cases which movement can be carried 20 out by hand by rotating in one direction or the other the hand wheel 28 positioned near the operator of the machine. The said slot also serves to rectify the direction of the poker in case a flexion should supervene. 25 The motor 25 is started and works continuously; it has keyed upon its armature a smooth friction pinion 29 made of raw hide or any other suitable material. Keyed upon a horizontal shaft 30 are two friction cones 31 adapted to be brought into contact with the smooth pinion; on the said shaft and on both sides of the said friction cones are two cast iron drums 32 having an inwardly curved rim and upon which 35 the cables driving the pokers are wound. The said drums are rotating loosely on the shaft 30 and are provided with ratchet teeth 33 corresponding to a coupling device sliding onto the shaft 30 through the medium of a key secured to said shaft. When 40 the apparatus is started the said coupling devices are not engaged with the claws of the drums and the smooth pinion rotates with a certain clearance between the friction cones.

When the operator desires to put into action one of the pokers, he engages first one of the drums 32 into the teeth of its coupling device; thereafter he exerts a pressure 45 on one of the ends of the shaft by means of a lever 35 in order to bring one of the cones into contact with the pinion. The shaft 30 at once starts rotating in one direction and causes the poker to advance and when at any desired moment, the operator wants to bring the poker back toward himself, all that is required is to exert a pressure by means of the same lever on the opposite end of the shaft so as to 55 bring the other cone into contact with the pinion of the motor. In order to well understand this working, it must be borne in mind that as the motor always rotates in the same direction, if one of the cones is brought into contact with the pinion, the horizontal

shaft will rotate in one direction and if the frictional engagement of this cone is stopped and the other cone engaged with the pinion, the shaft will rotate in the other direction without it being necessary to alter 70 the direction of rotation of the motor. Consequently, as at every desired moment it is possible to reverse the direction of rotation of the horizontal shaft and as the cables which actuate the pokers are carried on in 75 the direction of the rotation of the concave drums, it follows that the pokers follow the direction of movement of the cables and thus are adapted to perform a rapid reciprocating movement. Any other mechanical 80 system might be used to actuate the pokers.

Having now fully described our said invention, what we claim and desire to secure by Letters Patent, is:

1. In a mechanical poker, the combination of a spreading device comprising a carrier, means for adjusting the said carrier both vertically and horizontally, a plurality of pokers carried by said carrier, means for causing the said pokers to reciprocate on 90 said carrier, means for raising and lowering the front ends of said pokers and means for raising and lowering the rear ends of said pokers, substantially as and for the purpose set forth.

2. In a mechanical poker, the combination with a carrier, of means for adjusting said carrier both vertically and horizontally, a plurality of pokers mounted on said carrier, means for causing the pokers to reciprocate on 100 said carrier, said means comprising a motor, a friction pinion on said motor, a double internal friction wheel adapted to engage with either face of said pinion, a shaft carrying said wheel, and fast therewith, drums 105 loosely mounted on said shaft, cables carried by said drums and connected with said pokers, clutch devices adapted to engage said drums to cause them to rotate to move said pokers, and means for shifting the 110 friction wheel, to cause the pinion to engage either face thereof to change the direction of rotation.

3. In a mechanical poker, the combination with an adjustable carrier, of a plurality of reciprocating pokers, mounted thereon, means for controlling the movement of said pokers, and means for raising and lowering said pokers at the furnace end thereof, said means comprising a lever 115 carrying said poker, a pivoted lever having its short arm connected to the poker carrying lever, and a hand lever connected to the long arm of said pivoted lever.

4. In a mechanical poker, the combination with an adjustable carrier, of a plurality of controllable reciprocating pokers thereon, means for raising and lowering the furnace ends, and means for raising and lowering said pokers at the far end, said 125 130

means comprising a member carrying said poker, a pivoted bell crank lever attached to said member, the other arm of said lever having a threaded bushing, a threaded rod in said bushing, means for rotating said rod to move said bell crank lever, whereby to raise or lower said pokers.

In testimony whereof we have hereunto set our hands in presence of two witnesses.

OCTAVE BATTAILLE.
PIERRE PIPEREAUT.
